Filed Mar. 16, 1966, Ser. No. 1,496

Term of patent 14 years

(Cl. D54—12)

FIG. 1

FIG. 2

FIG. 3

FIG. 4

FIG. 5

FIG. 1 is a front elevational view of a spoon showing my new design;

FIG. 2 is a back elevational view of the spoon;

FIG. 3 is a side elevational view of the spoon;

FIG. 4 is an enlarged section taken on line 4—4 of FIG. 1;

FIG. 5 is an enlarged section taken on line 5—5 of FIG. 1; and

FIG. 6 is an enlarged section taken on line 6—6 of FIG. 3.

The essential features of my design for a spoon or similar article reside in the configuration of the handle in combination with the particular type of ornamentation as applied thereto.

I claim:

The ornamental design for a spoon or similar article, substantially as shown and described.
